[75] Inventor: Leslie J. Sell, Bothell, Wash.

Primary Examiner—Kay H. Chin

Attorney, Agent, or Firm—Walter C. Vliet

[73] Assignee: Ingersoll-Rand Company, Woodcliff
Lake, N.J.

[57] CLAIM

The ornamental design for a free-chain indicator knob
for a lever hoist, as shown and described.

[**] Term: 14 Years

DESCRIPTION

FIG. 1 is a top plan view of the free-chain indicator
knob for a lever hoist showing my new design;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a bottom plan view thereof.

The broken lines shown in FIGS. 1 through 6 are for
illustrative purposes only and form no part of the
claimed design.
